[57] CLAIM

The ornamental design for a faucet connector size guide, substantially as shown.

DESCRIPTION

FIG. 1 is a top perspective view of a faucet connector size guide showing our new design;

FIG. 2 is a top plan view thereof;

FIG. 3 is a bottom plan view thereof;

FIG. 4 is a left side elevational view as taken from line 4—4 of FIG. 1;

FIG. 5 is a right side elevational view as taken from line 5—5 of FIG. 1;

FIG. 6 is a top edge view of FIG. 2 as taken from line 6—6;

FIG. 7 is a cross sectional view of FIG. 2 as taken from line 7—7; and

FIG. 8 is a cross sectional view of FIG. 2 as taken from line 8—8.

FIG. 5
